UNITED STATES PATENT OFFICE.

WILLIAM M. THOMAS, OF PHILADELPHIA, PENNSYLVANIA.

FIREPROOF FLOOR CONSTRUCTION.

1,290,804.

Specification of Letters Patent.

Patented Jan. 7, 1919.

Application filed May 20, 1912, Serial No. 698,642. Renewed April 2, 1918. Serial No. 226,300.

To all whom it may concern:

Be it known that I, WILLIAM M. THOMAS, a citizen of the United States, residing at Philadelphia, in the county of Philadelphia and State of Pennsylvania, have invented a new and useful Fireproof Floor Construction, of which the following is a specification.

The main object of the present invention 10 is to dispense as far as possible, with the use of false work or molds in the construction of fireproof floors or ceilings.

A further object of the invention is to provide a fireproof floor construction in 15 which the floor and ceiling are formed of members molded to shape before being placed in position in the floor and ceiling, these members forming a flat ceiling with arches above the same, and forming the temporary support for concrete floor beams and 20 forming eventually, a part of the finished structure.

Other objects of the invention will appear hereinafter.

25 The accompanying drawings illustrate embodiments of the invention, and referring thereto:

Figure 1 is a vertical section of a portion of a floor, showing the same in process of 30 construction, according to one form of the invention.

Fig. 2 is a view similar to Fig 1, showing the application of another form of the invention.

35 Fig. 3 is a perspective of the arch and ceiling slab construction shown in Fig. 1.

Fig. 4 shows another form of the arch and ceiling slab construction.

40 Figs. 5 and 6 show further modifications of the arch and ceiling slab construction.

Fig. 7 is a vertical section of another form of the invention.

Fig. 8 is a section on line x^8-x^8 in Fig. 7.

45 The floor constructed according to my invention comprises as essential elements pre-formed arch beam members molded separately, pre-formed arch floor members resting on said beam members and molded concrete beams molded into the spaces between adjacent arch floor members.

50 In the form shown in Figs. 1 and 3, the pre-formed arch beam members are formed of tile or concrete formed with an arched upper portion 1, and a straight lower portion 2 connecting the ends of said arched portion, both the arched and straight por-

tions being preferably reinforced as indicated at 1' in Fig. 1 so as to form an arch member of great strength. At each side, the arch portion 1 is provided with a laterally extending flange 4 which is of arched shape to form a support for the arch sections of the floor. Said arch sections may be formed in two or more sections for each arch, each arch section 5 being formed, for 60 example, of hollow tile, as shown in Figs. 1 and 3, or of other suitable material as hereinafter set forth, said sections being provided with upper flat floor surfaces terminating in dovetail shoulders or outwardly 65 and upwardly projecting wall portions 6 and there being other dove-tail shoulders 7 at the outer ends of the sections, said shoulders being provided for interlocking with the main floor beams. The spaces between 70 the straight lower members 2 of the arch beams may be occupied and closed by ceiling slabs or plates 8 which extend across said space and are in contact with the straight portions 2 of the arch beams. In forming 75 the floor according to this form of the invention, temporary supporting posts 10 are placed in suitable positions and the arch beams above described placed thereon at suitable intervals, the ceiling slabs 8 being 80 placed between the arch beams to form a continuous ceiling. The arch floor sections 5 are then placed on the arch beams forming continuous surfaces between which are formed spaces for receiving and forming the 85 main floor beams, cement or concrete being 90 then poured into said spaces so as to form the main floor beams 12 which are in integral contact with the arch floor sections 5. The arch floor sections 5 being concavely 95 curved at their end portions so as to extend under the end portions of the arch ribs and having their outer end faces inclined toward the arch ribs in a downward direction, it follows that the cement floor beam molded 100 into the space between the arched floor sections is interlocked with said floor sections and said floor sections are interlocked with the arch beams so that when the cement beams 12 have set, they support both the 105 floor sections and the arch beams and the temporary supports 10 may then be removed. The beams 12 molded into position in this manner constitute T-beams, their upper portions expanding over the spandrels of the 110 arch members.

The arch beams instead of being made

hollow as in Fig. 3, may be made solid as shown at 15 in Figs. 2, 4 and 5. Fig. 2 also shows the arch sections formed of solid concrete members 16 in place of hollow tiles. 5 Moreover, as shown in Figs. 4 and 5, the arch sections may be made in more than two sections, there being a plurality of sections or voussoirs at each side of the center, such sections being shown as tiles 17 in Fig. 4, and 10 as concrete members 17' in Fig. 4. In case said arch beams are formed of concrete, they are preferably fastened to the ceiling slabs by means of pins or spikes 18 set or molded into the arch sections and projecting downwardly therefrom into plugs 20 of wood or 15 other penetrable material set into recesses or holes 21 in the ceiling slabs. In case tile arch sections are used, they are preferably held in position on the slabs by means of 20 clamps 24 formed of sheet metal having prongs or projections 25 extending downwardly into holes 26 in the ceiling slabs and extending up in contact with the ends of the arch sections as shown in Figs. 3 and 5. 25 The arch beams in place of being made of tile or concrete may be made of metal such as steel, as shown at 28 in Fig. 6, said beams being, for example, formed of angle-iron strips 29, bent to form the upper member 30 of the arch, strips 30 connecting the ends of said arch and bracing strips 31 connecting the upper and lower members 29 and 30 to form a trussed arch or bowstring truss. The upper members 29 of the arch are provided 35 with lateral flanges 32 on which rest the arch sections 33. Figs. 7 and 8 show a similar construction except that the lower strip 34 of the metallic arch is provided with lateral projections 35 on which rest tile or molded ceiling 40 sections or slabs 36, and the upper or arch member 37 of the arch beam is provided with bent portions 37' at the end extending over tiles or bricks 39 which form the end members 45 of the arch sections which incline inwardly toward the center of the arch, so as to give

an interlock with the floor beams when they are molded into the spaces between the arch sections. The remainder of the arch sections may be formed of a plurality of bricks or tiles 40 set on top of the arch member 37. 50 The horizontal lower member 41 of the metallic arch beam may extend, as shown at 41', into the concrete floor beams, so as to relieve the floor beams of side thrust from the arch sections. 55

What I claim is:

1. In combination, pre-formed arch beam members, having laterally extending flanges, pre-formed arch floor members having their side edges seated on said flanges and having 60 upper flat floor surfaces, and main floor beams molded between and over the ends of adjacent arch floor members and flush with the flat floor surfaces thereof.

2. In combination, pre-formed arch beam 65 members having laterally extending flanges, pre-formed arch floor members having their side edges seated on said flanges and having upper flat floor surfaces terminating in dove-tail shoulders, and main floor beams molded 70 between and over the ends of adjacent arch floor members and molded between adjacent dove-tail shoulders.

3. In combination, pre-formed arch beam members having laterally extending flanges, 75 pre-formed arch floor members having their side edges seated on said flanges and having dove-tail shoulders between the ends of said floor members, and main floor beams molded between and over the ends of adjacent arch 80 floor members and molded between adjacent dove-tail shoulders to form T-shaped beams.

In testimony whereof, I have hereunto set my hand at Los Angeles, California, this 14th day of May, 1912.

WILLIAM M. THOMAS.

In presence of—

ARTHUR P. KNIGHT,
MARTHA M. LANGE.
